 Ingersoll-Rand Company, Jersey City, N. J., a
 corporation of New Jersey

Application September 30, 1939, Serial No. 297,311

6 Claims. (Cl. 121—5)

This invention relates to rock drills, and more particularly to a controlling device for the feeding mechanism of rock drills of the fluid actuated type.

One object of the invention is to effect the automatic release of the feeding element from the motor whereby it is driven in the event of undue resistance to rotation of the working implement actuated by the rock drill.

Other objects will be in part obvious and in part pointed out hereinafter.

In the drawings accompanying this specification and in which similar reference numerals refer to similar parts,

Figure 1 is a longitudinal elevation, partly broken away, of a portion of a rock drill equipped with a controlling device constructed in accordance with the practice of the invention,

Figure 2 is a transverse view taken through Figure 1 on the line 2—2 looking in the direction indicated by the arrows,

Figure 3 is a transverse view taken through Figure 1 on the line 3—3, and

Figure 4 is a diagrammatic view, partly broken away, of the controlling device and a portion of the rock drill.

Referring more particularly to the drawings, 20 designates, in general, a drilling mechanism comprising a rock drill 21 and a shell 22 to guide the rock drill with respect to the work.

The rock drill 21 comprises a cylinder 23 having a piston chamber 24 to accommodate a hammer piston 25 reciprocable in the piston chamber 24 for actuating a drill steel (not shown). The pressure fluid used to actuate the piston 25 is 25 valved to the piston chamber 24 by suitable valve mechanism 26 arranged rearwardly of the piston chamber 24 and of which only the chest is shown, and seated on the rearward end of the valve mechanism 26 is a motor 27 serving the dual function of imparting rotary movement to the drill steel and to move the rock drill 21 relatively to the shell 22 for maintaining the drill steel in substantially the correct position with respect to the work.

The motor 27 is of the uni-directional, rotary vane type. It comprises a cylinder 28 which may be keyed to the cylinder 23 in any suitable manner and has a piston chamber 29 to accommodate a rotor 30 containing radially slidable vanes 31 against which pressure fluid acts for rotating the rotor. The rotor 30 is mounted upon and keyed to a shaft 32 extending beyond the ends 35 of the cylinder 28 into the valve chest 26 and

into a cylinder extension 33 forming a closure for the rear end of the cylinder 23.

The end of the shaft 32 lying within the cylinder extension 33 carries a pinion 34 that meshes with a gear 35 of a transmission shaft 36 journaled in the extension 33. The shaft 36 has a pinion 37 intermediate its ends to mesh with a gear 38 of a shaft 39 extending forwardly along the rock drill cylinder to drive the chuck mechanism (not shown) wherewith the drill steel is 10 slidably interlocked, in a well known manner.

The motion required for effecting feeding movement of the rock drill relatively to the shell 22 is also transmitted by the shaft 36. This shaft is accordingly provided with a pinion 40, on its 15 rearward end, to mesh with a pair of gears 41 and 42 of which the gear 42 is an internal gear and encircles the gear 41. The gears 41 and 42, respectively, constitute portions of driving members 43 and 44 arranged in a recess 45 in the opposed ends of the cylinder extension 33 and a back head 46 forming the rearmost casing part of the rock drill.

The gear 41 has an integral sleeve 47 which is 25 rotatable upon a stationary shaft 48 seated in the extension 33 and the back head 46. The rearward end of the sleeve 47 forms a seat for the driving member 43 which is clamped against a shoulder 49 on the sleeve 47 by a nut 50. The 30 driving member 44 may, as shown, form an integral part of the gear 42, and between said driving member and the gear 42 is an anti-friction bearing 51 the inner race of which is seated directly on the sleeve 47.

In the opposed surfaces of the driving members 43 and 44 are piston chambers 52 and 53, respectively, to receive pistons 54 and 55 which have a sufficiently loose fit in the piston chambers to permit of a moderate degree of leakage 40 of fluid medium across their peripheries into the recess 45. The pistons are carried by a sprocket wheel 56 arranged between the driving members and the outermost ends of the pistons 54 and 55 45 constitute friction surfaces 57 adapted to engage friction discs 58 arranged in the bottoms of the piston chambers 52 and 53.

The sprocket wheel 56 is rotatable on and slideable longitudinally of the sleeve 47 and engages 50 a chain 59 which is trained over sprocket teeth 60 carried by a feed nut 61 journaled in a lug 62 on the cylinder extension 33. The feed nut is freely rotatable in the lug 62 and is in threaded engagement with a feed screw 63 extending there- 55

through and longitudinally of the shell 22 which supports the feed screw.

Normally the feed screw 63 remains stationary and may be held thus by a latch 64 having a 5 detent 65 to engage notches 66 in a flange 67 near the rear end of the feed screw. The latch is maintained in locking engagement with the feed screw by a spring 68, and on the rearward extremity of the feed screw is the usual crank 69 whereby the feed screw may be manually rotated, 10 if desired.

In order that the sprocket wheel may be conveniently actuated into and held in frictional engagement with the friction discs 58 for rotating the feed nut 61 in one direction or the other, depending upon the direction in which it is desired to actuate the rock drill relatively to the shell, the ends of the pistons 54 and 55 adjacent the friction discs 58 serve as actuating surfaces 20 70 and 71, respectively, against which pressure fluid acts for shifting the sprocket wheel relatively to the friction discs. The pressure fluid employed for thus shifting the sprocket wheel 56 is conveyed to the piston chambers 52 and 25 53 by inlet passages 72 and 73. The passages 72 and 73 lead through the shaft 48 and the cylinder extension 33 to a valve chamber 74, in the extension 33, containing a throttle valve 75 of the rotary type for controlling the passages 30 72 and 73.

Within the throttle valve is a bore 76 into which pressure fluid may flow, in the extreme positions of the throttle valve, through ports 77 and 78 radiating from the bore 76 and adapted 35 to register with a passage 79 leading to a supply chamber 80 in the extension 33. The throttle valve 75 is, moreover, provided with two sets of ports of which the ports of a set are angularly disposed with respect to each other. Each of 40 these sets of ports serves to communicate the bore 76 with the passages leading to the piston chambers in the driving members. Those associated with the passage 72 are designated 81 and 82 and the ports intended to register with 45 the passage 73 are designated 83 and 84.

In the periphery of the throttle valve 75 and in the transverse planes of the points of communication of the passages 72 and 73 with the valve chamber 74 are partly annular grooves 85 and 86 to afford communication with exhaust ports 87 for opening the piston chambers 52 and 53 to the atmosphere.

The supply chamber 80 is in constant communication with a source of pressure fluid supply 55 through a conduit 88 connected to the cylinder extension 33, and adjacent the supply chamber 80 is a second throttle valve 89 for controlling the admission of pressure fluid to the motor 27 and the valve mechanism 26. The throttle valve 89 is preferably of the same type as the throttle valve 75 and has a bore 90 to convey pressure fluid to a port 91, in the wall of the throttle valve, registering with a passage 92 leading to the valve mechanism 26. The throttle valve 89 has a second port 93 to register with a passage 94 leading through the extension 33 and the motor cylinder 28 to the piston chamber 29.

Under certain conditions of operation, the pressure fluid used for shifting the sprocket wheel 56 into engagement with the friction discs 58 is controlled by manipulation of the throttle valve 75, as, for example, when first starting a 70 drill hole or when the force operating to retract the drill steel from the drill hole meets little or 75 no resistance from the cuttings in the drill hole.

During normal drilling, however, the supply of pressure fluid to the piston chambers 52 and 53 is preferably controlled automatically so that if resistance to the rotation of the drill steel in the drill hole becomes excessive, the driving connection 5 between the motor and the feeding mechanism may be automatically disconnected in order that the power of the motor 27 may be applied exclusively to the rotation mechanism of the rock drill for freeing the drill steel. In furtherance 10 of this end the rock drill is provided with valve mechanism designated in its entirety by 95 that acts responsively to fluctuations in the pressure fluid flowing to the motor 27 for valving pressure fluid to the piston chambers 52 and 53. 15

The valve mechanism 95 is located in the cylinder extension 33. It comprises a bushing 96 the interior of which constitutes a valve chamber 97 to accommodate a reciprocating valve 98 having a pair of heads 99 and 100 connected by a 20 reduced stem 101.

In the forward end of the bushing 96 is a bridge 102 which forms a seat for an extension 103 at the forward end of the head 100 of the valve. The rearward end of the valve seats 25 against a spring 104 which is interposed between the valve and the end surface of the valve chamber 97 to retain the extension 103 against the bridge 102. Preferably, the portion of the valve chamber 97 containing the spring 104 is communicated with the recess 45 by a port 105 in the extension 33 and the recess 45 is, in turn, open to the atmosphere through a port 106 in the back head 46.

The pressure fluid supplied to the motor 27 35 passes through the valve chamber 97 across a pressure surface 19 on the front end of the head 100. The bushing 96 is accordingly provided with a port 107 which is so located with respect to the front end of the head 100 of the valve 98 40 that normally only a portion of the port will be uncovered by the head 100 which controls said port.

The bushing 96 is provided with another port 108 located immediately rearwardly of the head 45 100 whereby it is controlled and said port 108 opens into the branch of the passage 94 leading from the valve mechanism 95 to the throttle valve 89 to convey pressure fluid into the valve chamber 97 between the heads 100 and 99. The 50 pressure fluid thus admitted into the intermediate portion of the valve chamber 97 passes therefrom through ports 109 opening into a supply passage 110 leading to the throttle valve chamber 74, and in the throttle valve 75 are a 55 pair of relatively angularly disposed ports 111 and 112 to afford communication between the supply passage 110 and the bore 76 in different positions of the throttle valve 75.

As is customary, the rock drill is provided with 60 a water tube 113 extending coaxially through the rock drill for supplying cleansing fluid to the drill hole to flush the cuttings therefrom. The water tube 113 may be of any well known type and is secured in position by a plug 114 threaded 65 into the rearmost end of the back head 48.

As a first step in the operation of the device, and assuming that it is intended to move the rock drill toward the work to actuate the drill steel thereinto, the throttle valve 89 is opened 70 to admit pressure fluid to the passages 92 and 94 and thus to the valve mechanism 26 and the motor 27. The valve mechanism 26 will then operate to distribute pressure fluid to the ends of the piston chamber 24 for actuating the piston 75

25 against the drill steel. At the same time the motor 27 is set in operation and its movement is transmitted through the shaft 36 to the shaft 39 for rotating the drill steel to new positions 5 between the blows of the hammer piston.

Simultaneously with or immediately following the starting of the motor 27 and the percussive element of the drill the valve 75 is rotated to the position shown in Figure 4 in which the port 77 10 registers with the passage 79 and the port 83 registers with the passage 73. Pressure fluid then flows from the supply chamber 80 to the piston chamber 53 against the actuating surface 57 and shifts the sprocket wheel 56 into frictional engagement with the adjacent friction disc 58 carried by 15 the driving member 43.

The sprocket wheel 56 will then rotate with the driving member 43 and its rotary movement is transmitted through the chain 59 to the feed 20 nut 61 which will then be rotated relatively to the feed screw so that the rock drill 21 will be advanced along the shell 22 toward the work in accordance with the penetration of the drill steel thereinto. In this way the percussive element of 25 the rock drill will be constantly maintained in the correct operative relationship with the drill steel.

The throttle valve 75 remains in the position described until the drill hole has been started and is then shifted to a position in which the 30 port 71 is moved out of registry with the passage 79 and the port 111 registers with the supply passage 110 and the port 84 registers with the passage 73. Pressure fluid then flows from the valve chamber 97 through the supply passage 110 and associated passages into the piston chamber 53 for holding the sprocket wheel in engagement with the driving member 43.

In the new position of the throttle valve 75 the 40 supply of pressure fluid will be controlled only by the valve 98, the pressure surface 19 of which is constantly exposed to the value of the pressure fluid flowing to the motor 27. Thus, if during the ensuing operation of the drilling mechanism, the resistance to the rotation of the motor increases, as when a collar of detritus on the drill steel tends to bind it in the drill hole, the pressure acting against the pressure surface 19 will closely approach or rise to nominal, it being understood that during the normal relatively free rotation of 45 the motor the pressure forwardly of the pressure area will drop materially below nominal by reason of the restricted area of communication through the port 107 between supply and the front end of the valve chamber 97.

50 The increased pressure acting against the pressure surface 19 will then move the valve 98 rearwardly over the port 108 to reduce or fully cut off the flow of pressure fluid into the valve chamber 97. By reason of this throttling action of the valve 98 the supply of pressure fluid to the piston chamber 53 will be diminished or entirely cut off and owing to the slight clearance between the periphery of the piston 55 and the wall of the piston chamber 53 the pressure fluid will leak from the 55 piston chamber 53 and release the sprocket wheel 56 from the driving member 43.

By thus releasing the sprocket wheel the feeding mechanism will be disconnected from the motor and the power of the latter will then be applied only to the rotation mechanism for turning the drill steel. After the drill steel is again free to rotate the speed of the motor 27 will increase. Consequently, there will then be a reduction 70 in the pressure forwardly of the pressure surface 19 and the spring 104 will shift the valve for-

wardly to restrict the flow area of port 107 and to uncover the port 108. A full supply of pressure fluid will thereby be admitted to the piston chamber 53 and the sprocket wheel will again be actuated into frictional engagement with the driving member 43. 5

After the drill steel has penetrated the work to the limit of its extent the throttle valve 75 is rotated to a new position in which the port 112 registers with the passage 110 and the port 82 registers with the passage 72. Pressure fluid will then flow from the valve chamber 97 through the supply passage 110, the bore 76 of the throttle valve and through the passage 72 into the piston chamber 52 and press the sprocket wheel 56 into engagement with the friction disc 58 carried by the driving member 44. The sprocket wheel and the associated elements will then be driven in a direction to cause retractive movement of the rock drill along the shell 22, and during such movement of the rock drill the valve 98 will operate in the manner previously described to effect the release and the reengagement of the sprocket wheel with the driver 44 whenever abnormalities in the drill hole hinder the rotative movement of the drill 20 steel. 25

In the event that the rock being drilled has little or no tendency to create a condition that might necessitate the breaking of the driving connection between the sprocket wheel and the 30 driving element during the retractive movement of the rock drill the throttle valve 75 may be placed in a position in which the port 78 is in registry with the passage 79. In this position the throttle valve 75 will blank off the supply passage 110 and 35 the port 81 will be in registry with the passage 72. Pressure fluid may then flow directly from the supply chamber 80 through these channels into the piston chamber 52 for holding the sprocket wheel 56 in engagement with the driver 44. 40

In practice, the present invention has been found to be a highly desirable device for automatically relieving the motor 27 whenever the load thereon becomes excessive. This is of great advantage in rock drills of the character described 45 for the reason that it eliminates the necessity of constant attention and frequent manipulation of the various controlling elements of the rock drill to maintain the drill steel free in the drill hole. 50

I claim:

1. A controlling device, comprising a casing, a fluid actuated motor, means driven by the motor, fluid actuated clutch means to form a connection between the motor and the first mentioned means, a valve to control the flow of pressure fluid to the 55 clutch means, and a pressure surface on the valve subjected to the fluctuations in the pressure of the fluid flowing to the motor for actuating said valve.

2. A controlling device, comprising a casing, a plurality of pressure fluid actuated devices in the 60 casing, a passage for constantly conveying pressure fluid to one of the devices, a channel for conveying pressure fluid to another device, a valve to control the flow of pressure fluid through the channel, a pressure surface on the valve constantly subjected 65 to the fluctuations in the pressure of the fluid in the passage for actuating the valve to throttle the channel, and means for selectively communicating one of the devices with the channel and with a source of pressure fluid supply. 70

3. A controlling device, comprising a casing having a pressure fluid supply chamber, a driven member, a fluid actuated motor for driving the driven member, a clutch to form a connection between the motor and the driven member and hav- 75

ing an actuating surface, a valve acting responsive-
sively to the fluctuations in the pressure of the
fluid flowing to the motor for controlling the flow
of pressure fluid to the actuating surface, and
means for selectively communicating the actuating
surface with the supply chamber and with the
valve.

4. A controlling device, comprising a casing, a
driven member, a fluid actuated motor for driving
the driven member, a clutch to form a connection
between the motor and the driven member and
having opposed actuating surfaces, a supply chan-
nel in the casing, a valve acting responsive-
sively to the fluctuations in the pressure of the fluid flowing
to the motor for valving pressure fluid to the supply
channel, and means for selectively communicating the
actuating surfaces with the supply channel.

5. A controlling device, comprising a casing hav-
ing a pressure fluid supply chamber, a driven mem-
ber, a fluid actuated motor for driving the driven
member, a clutch to form a connection between the
motor and the driven member and having opposed
actuating surfaces, a supply channel in the cas-
ing, a spring-pressed valve acting responsive-
sively to the fluctuations in the pressure of the fluid flowing
to the motor for valving pressure fluid to the supply
channel, and means for selectively communicating the
actuating surfaces with the supply channel.

the fluctuations in the pressure of the fluid flowing
to the motor for valving pressure fluid to the
supply channel, and a manually operable valve
for selectively communicating the actuating sur-
faces with the supply chamber and with the sup-
ply channel.

6. A controlling device, comprising a casing hav-
ing a pressure fluid supply chamber, a driven mem-
ber, a fluid actuated motor for driving said mem-
ber, a clutch to form a connection between the 10
motor and the driven member and having opposed
actuating surfaces, a supply channel in the cas-
ing, a spring-pressed valve acting responsive-
sively to the fluctuations in the pressure of the fluid flow-
ing to the motor for valving pressure fluid to the 15
supply channel, and a throttle valve movable to
different positions for cutting off communication
between the supply channel and the actuating sur-
faces and to simultaneously communicate the act-
uating surfaces selectively with the supply cham-
ber and said throttle valve being movable to other
positions to selectively communicate the actuating
surfaces with the supply channel.

WILLIAM A. SMITH, SR.
